UNITED STATES PATENT OFFICE.

FRANK CALDWELL, OF CINCINNATI, OHIO.

APPARATUS FOR FEEDING POWDERED OR PULVERIZED FUEL.

1,231,488.

Specification of Letters Patent. Patented June 26, 1917.

Application filed September 26, 1916. Serial No. 122,228.

To all whom it may concern:

Be it known that I, FRANK CALDWELL, a citizen of the United States, and a resident of Cincinnati, in the county of Hamilton 5 and State of Ohio, have invented a certain new and useful Improvement in Apparatus for Feeding Powdered or Pulverized Fuel, of which the following is a specification.

My present invention relates generally to 10 apparatus for feeding fuel, and more particularly to apparatus for feeding powdered or pulverized fuel by the use of an air jet, the air co-mingling with fuel in its passage to the point of consumption.

15 The object of my present improvement is to provide such an apparatus including a delivery pipe having a delivery nozzle and further provided with means in the form of a tortuous passage preceding its delivery 20 end whereby the air and the powdered or pulverized fuel are checked in their forward movement without undue retardation, to secure their effective admixture or commingling for the purpose of increasing combustion 25 at the point of consumption.

Another object of the invention is to provide a simple apparatus, in which provision is made for the suitable heating of the fuel and the air and the mixture thereof, in order 30 to insure of a dry state and a sufficient temperature to avoid chilling the gases within the furnace or other point of consumption.

With the above in mind, my invention 35 resides in the features of construction, arrangement and combination, as hereinafter pointed out, reference being made to the accompanying drawings, forming a part of this specification, wherein:—

40 Figure 1 is a vertical longitudinal section through my improvement, and illustrating the same in connection with the fire-box of a furnace or other combustion space.

Fig. 2 is a vertical transverse section 45 taken therethrough substantially on line 2—2 of Fig. 1;

Fig. 3 is an enlarged longitudinal section through a portion of the delivery pipe; and

Fig. 4 is an end view of the delivery 50 nozzle.

Referring now particularly to these figures, the powdered or pulverized fuel is fed from a hopper 10, by means of a fluted or otherwise formed feed roller 11 at the 55 lower delivery opening 12 of said hopper, the hopper being provided with a jacket 13

forming a steam space 14 between the same and the wall of the hopper and entirely surrounding the latter, into which leads the upper end of a steam pipe 15.

The lower delivery end of the hopper 10 opens into a horizontally extending casing 16 inclosing a screw conveyer 17, longitudinally of the casing, and by means of which, in conjunction with the fluted or otherwise formed feed roller 11, a substantially uniform feed of the powdered or pulverized fuel may be had at the tapering delivery opening 18 of the casing 16 located at the relatively opposite end thereof, from the 70 hopper 10.

The feed screw 17 is mounted upon a shaft 19, having one end thereof projecting beyond the respective end of the casing 16 and provided with a pulley 20 by which the 75 screw may be connected with a suitable source of power. The roller 11 is likewise mounted upon a shaft 21 projecting laterally beyond one side of the hopper 10, as best seen in Fig. 2, and provided with a pulley 22 80 for belt connection with a suitable source of power.

Below the casing 16 is a second casing 23 longitudinally through which projects the delivery pipe 24, this pipe extending beyond 85 both ends of the casing 23, for connection at one end to a suitable source of air supply, and for connection at its opposite end with a delivery nozzle 25, the delivery end of the latter as best seen in Fig. 4, being 90 flared and flattened as at 26, and the connection of pipe 24 therewith being by means of a flexible union 27, whereby the nozzle 25 may be adjusted vertically in the opening 28 of a fire box 29 with a plate 29^a secured in vertical adjustment upon the wall of the fire box and held as by means of a clamping nut 30.

Intermediate the ends of the casing 23, the feed pipe 24 is provided with an abruptly inclined portion 31 and with a helically coiled portion 32, the latter being between the inclined portion 31 and the nozzle 25, as seen by reference to Fig. 1.

The casing 23 is provided with a depending portion 33, intermediate its ends, for forming a continuation of the tapering outlet 18 of the screw casing 16 to receive the substantially uniform supply of powdered or pulverized fuel. To the lower portion of 110 the part 33 of the casing 23 is secured the abruptly inclined portion 31 of the delivery

pipe 24, as clearly seen by reference to Figs. 1 and 2, the connection being made by a strap or other fastening 34, so as to maintain the abruptly inclined portion 31 in proper relation to the feed channel for the fuel to receive such fuel through its upper longitudinal slot 35 as seen in Fig. 3, the fuel so entering pipe 24 falling upon a diaphragm 36 from the lower end of which it 10 is continually drawn into the current of air passing through pipe 24, so that the air and fuel thus joined will be checked in their movements through the helix 32 of the pipe and intimately mixed or co-mingled therein 15 before delivery from the nozzle 25 without undue retardation.

The casing 23 forms a steam chamber and to this end is provided with a valved steam supply pipe 37, as well as an outlet valve 20 38, for condensation, the pipe 15 before described leading from the casing 23 so as to supply steam therefrom to the space 14 around the hopper 10. The air as well as the powdered or pulverized fuel will thus 25 be heated sufficiently even before their admixture to thoroughly dry the same and increase their temperatures both before and after admixture to such a point as to avoid all danger of chilling the gases within the 30 fire box or other source of consumption or combustion of the fuel.

It is obvious in operation that the nozzle 25 may be adjusted vertically, as desired, and provided with a substantially continuous 35 uniform combustible mixture through the uniform feed of the fuel as before described and the uniform air supply, and that the air being as usual under pressure, will discharge the mixture in a spray or thin 40 film into the fire box or combustion space, whereby to provide for its ready ignition and thorough consumption, as well as the maximum units of heat from its use.

It is furthermore obvious that as far as 45 the powdered or pulverized fuel is concerned, wood, grain, coal or other material may and can be utilized.

I claim:

1. In an apparatus of the character described, the combination of a supply hopper, 50 having a jacket forming a steam space there-around, a casing forming a steam chamber and having connection with the said jacket for supplying steam thereto in order to dry the material within the hopper, an air supply pipe extending through the said steam casing and having a fuel inlet and a helically coiled portion therein beyond the said fuel inlet; an injecting nozzle connected to one end of the said pipe nearest the said 55 coiled portion thereof, and means for feeding the fuel uniformly from the said hopper to the said fuel inlet of the supply pipe.

2. In a device of the character described, the combination of an air supply pipe having an injecting nozzle at one end, and an intermediate fuel receiving opening, said pipe having a helix therein between the said fuel receiving opening and the said nozzle, a casing forming a steam chamber and surrounding the said helix and fuel intake opening of the said air supply pipe, and having a tapering feed channel leading into the said inlet opening of the pipe, and means whereby to feed fuel through the said channel for the purpose described.

3. In an apparatus of the character described, the combination of a feed channel, means for feeding pulverized fuel uniformly to the said feed channel, an air supply pipe having an intermediate angular portion disposed adjacent said feed channel and provided with an opening to receive fuel from the said feed channel and with an intermediate diaphragm downwardly upon 80 which the fuel is movable into the current of air passing through the pipe, said pipe having a delivery nozzle at one end and a helix therein between the said angular portion and the said delivery nozzle whereby 85 to check movement of the air and fuel and thoroughly mix the same without undue retardation.

FRANK CALDWELL.
